A. J. REEDY

OVEN

Filed Nov. 11, 1922

UNITED STATES PATENT OFFICE.

ALFRED J. REEDY, OF BATTLE CREEK, MICHIGAN, ASSIGNOR TO A-B STOVE COMPANY, OF BATTLE CREEK, MICHIGAN.

OVEN.

Application filed November 11, 1922. Serial No. 600,246.

To all whom it may concern:

Be it known that I, ALFRED J. REEDY, a citizen of the United States, residing at Battle Creek, county of Calhoun, State of Michigan, have invented certain new and useful Improvements in Ovens, of which the following is a specification.

This invention relates to improvements in ovens.

10. The main object of this invention is to provide an improved oven for gas stoves and the like, in which the parts are economical in structure and may be very readily assembled with a minimum of bolts, and one 15 which is very attractive and finished in appearance.

Further objects, and objects pertaining to structural details will definitely appear from the detailed description to follow.

20. I accomplish the objects of my invention by the devices and means described in the following specification. The invention is clearly defined and pointed out in the claims.

25. A structure which is a preferred embodiment of my invention is clearly illustrated in the accompanying drawing forming a part of this application, in which:

Fig. I is a front perspective view of a 30 gas stove embodying the features of my invention, the legs being partially broken away.

Fig. II is a detail vertical section on a line corresponding to line 2-2 of Fig. I.

35. Fig. III is a detail vertical section on a line corresponding to line 3-3 of Fig. I.

Fig. IV is a detail horizontal section on a line corresponding to line 4-4 of Fig. I.

Fig. V is a detail section on a line corresponding to line 5-5 of Fig. I.

40. In the drawing the sectional views are taken looking in the direction of the little arrows at the ends of the section lines and similar reference characters refer to similar parts throughout the several views.

45. Referring to the drawing, my improved oven comprises a front frame 1 formed up from sheet metal into a channel cross section and having a longitudinal bead 2 struck out therefrom to add to the appearance and to also add stiffness. This frame comprises side members 3 and a top member 4. The outer arms 5 of the frame are turned inwardly upon themselves providing seam members 6.

The side walls 7 and back 8 are preferably formed in one piece, the side walls having out-turned seam members 9 at their forward edges which are engaged with the seam members 6 of the front frame by a longitudinal 60 telescoping movement. The side walls 7 are provided with out-turned seam flanges 11 at their upper edges while the top 12 has coacting down-turned flanges 13 at its side edges which are engageable with the flanges 65 11 by a longitudinal telescoping movement of the top, the front edge of the top lying under the outer arms of the frame top member as shown in Fig. III.

The top is provided with a down-turned 70 flange 14 at its rear edge which overlaps the rear wall 8 and is secured thereto by the bolts 15. An angled supporting strip 20 is secured to the top member of the front frame to support the front edge of the top 75 12. This strip is supported by the bolts 21. The keeper 22 of the door 23 is also secured by one of these bolts. The parts are further secured thereto by the coacting pairs of outer and inner corner irons 16 and 17, the 80 irons 16 being arranged over the upper corners of the frame and constituting ornamental members, while the irons 17 are arranged within the frame and the corners clamp the walls 7 and 12, the screws 18 85 clamping the parts together.

The linings 19 are secured to the inner arms of the frame members.

With the parts thus formed and arranged, they are very rapidly assembled, and the 90 structure when assembled is strong and attractive in appearance.

Having thus described my invention what I claim as new and desire to secure by Letters Patent is:

1. In an oven, the combination of a front frame of channel cross section comprising top and side members, the outer arm of the frame being turned inwardly upon itself, providing a seam member, integral side and 95 rear walls, the side walls having out-turned seam members at their forward edges engageable with said seam members of said frame by a longitudinal telescoping movement, said side walls having out-turned seam 100 members on their upper edges, a top having down-turned seam members on its side edges engageable with said seam members at the top of said side walls with a longitudinal telescoping movement, the front edge of said 105 110

top being engaged under the outer arm of the frame top member, said top having a down-turned flange at its rear edge overlapping and secured to the rear wall, coacting 5 pairs of inner and outer corner irons for the top corners of said frame, clamping screws for said corner irons whereby the inner corner irons are clamped upon the top and side walls, and inner walls supported by the inner arms of said frame.

2. In an oven, the combination of a front frame of channel cross section comprising top and side members, the outer arm of the frame being turned inwardly upon itself 15 providing a seam member, integral side and rear walls, the side walls having out-turned seam members at their forward edges engageable with said seam members of said frame by a longitudinal telescoping movement, said side walls having out-turned seam members on their upper edges, a top having down-turned seam members on its side edges engageable with said seam members at the top of said side walls with a longitudinal 20 telescoping movement, the front edge of said top being engaged under the outer arm of the frame top member, and inner walls supported by the inner arms of said frame.

3. In an oven, the combination of a front 30 frame of channel cross section comprising integral top and side members having a longitudinal bead struck outwardly therefrom, the outer arm of the frame being turned inwardly upon itself providing a seam member, integral side and rear walls, the side walls having out-turned seam members at their forward edges engageable with said seam members of said frame by a longitudinal telescoping movement, said side walls 35 having out-turned seam members on their upper edges, a top having down-turned seam members on its side edges engageable with said seam members at the top of said side walls with a longitudinal telescoping movement, the front edge of said top being engaged under the outer arm of the frame top member, and inner walls supported by the inner arms of said frame.

4. In an oven, the combination of a front 50 frame of channel cross section comprising top and side members, the outer arm of the frame being turned inwardly upon itself providing a seam member, side walls, the side walls having out-turned seam members 55 at their forward edges engaged with said seam members of said frame, said side walls having out-turned seam members on their upper edges, a top having down-turned seam members on its side edges engaged with said seam members in the top of said side walls, the front edge of said top being engaged under the outer arm of the frame top member, coacting pairs of inner and outer corner irons for the top corners of said frame, 60 clamping screws for said corner irons where-

by the inner corner irons are clamped upon the top and side walls, and inner walls supported by the inner arms of said frame.

5. In an oven, the combination of a front frame of channel cross section comprising 70 top and side members, the outer arm of the frame being turned inwardly upon itself providing a seam member, side walls, the side walls having out-turned seam members at their forward edges engaged with 75 said seam members of said frame, said side walls having out-turned seam members on their upper edges, a top having down-turned seam members on its side edges engaged with said seam members in the top of 80 said side walls, the front edge of said top being engaged under the outer arm of the frame top member, and inner walls supported by the inner arms of said frame.

6. In an oven, the combination of a front 85 frame of angled cross section disposed to face inwardly and comprising top and side members, the outer arm of the frame having an in-turned seam member, walls having out-turned seam members at their forward edges engageable with said seam members of said frame by a longitudinal telescoping movement, said walls having out-turned seam members on their upper edges, 90 a top having down-turned seam members on its side edges engageable with said seam members at the top of said side walls with a longitudinal telescoping movement, the front edge of said top being engaged under the outer arm of the frame top member, 95 coacting pairs of inner and outer corner irons for the top corners of said frame, and clamping screws for said corner irons whereby the inner corner irons are clamped upon the top and side walls.

7. In an oven, the combination of a front frame of angled cross section disposed to face inwardly and comprising top and side members, the outer arm of the frame having an in-turned seam member, walls having out-turned seam members at their forward edges engageable with said seam members of said frame by a longitudinal telescoping movement, said walls having out-turned seam members on their upper edges, and a top having down-turned seam members on its side edges engageable with said seam members at the top of said side walls with a longitudinal telescoping movement, the front edge of said top being engaged under the outer arm of the frame top member.

8. In an oven, the combination of a front frame of angled cross section disposed to face inwardly, the outer arm of the frame 110 providing a seam member, walls having out-turned seam members at their forward edges engaged with said seam members of said frame, said walls having out-turned seam members on their upper edges, a top hav-

ing down-turned seam members on its side edges engaged with said seam members at the top of said side walls, coacting pairs of inner and outer corner irons for the top 5 corners of said frame, and clamping screws for said corner irons whereby the inner corner irons are clamped upon the top and side walls.

9. In an oven, the combination of a front 10 frame of angled cross section disposed to face inwardly and comprising top and side members, the outer arms of the frame side members providing seam members, side

walls having seam members at their forward edges engaged in said seam members 15 of said frame, said side walls having seam members on their upper edges, and a top having seam members on its side edges engaged with said seam members at the top of said side walls, the front edge of the top 20 being engaged with the outer arm of said frame top member.

In witness whereof, I have hereunto set my hand and seal.

ALFRED J. REEDY. [L. s.]
